FIG. 5

UNITED STATES PATENT OFFICE.

LAWRENCE BENSON AND WALLACE ABRAMS, OF NEWARK, NEW JERSEY.

PUMP.

No. 889,430.

Specification of Letters Patent.

Patented June 2, 1908.

Application filed December 28, 1907. Serial No. 408,343.

To all whom it may concern:

Be it known that we, LAWRENCE BENSON and WALLACE ABRAMS, citizens of the United States, residing at Newark, in the county of

5 Essex and State of New Jersey, have invented certain new and useful Improvements in Pumps; and we do hereby declare the following to be a full, clear, and exact description of the invention, such as will enable others 10 skilled in the art to which it appertains to make and use the same, reference being had to the accompanying drawings, and to characters of reference marked thereon, which form a part of this specification.

15 Our present invention relates, generally, to improvements in pumps; and, this invention has reference, more particularly, to a novel pump, which is especially adapted for use with the systems of piping through which 20 such liquids as beer, or the like, are conducted, and is for the purpose of forcing a cleaning compound or liquid through the pipes for cleansing the same.

Our invention has for its principal object 25 to provide a novel pump for cleaning purposes of the general character herein set forth, which is very simple in its construction, is easily manipulated, and is most efficient in its operations.

30 A further object of this invention is to provide a pump in which the plunger or piston is provided with an adjustable or regulatable means which can be set by the operator, so that the liquid can be continuously forced 35 through the pump-casing or cylinder in either direction, as may be desired; or, the regulating means may be set down tight upon the plunger or piston, so that the liquid will be sucked into the pump-casing or cylinder, at 40 the one end of the same and during the return-stroke of the plunger or piston again forced from the cylinder at the same end.

Other objects of this invention not at this time more particularly specified will be 45 clearly understood from the following detailed description of the same.

With the various objects of our present invention in view, the said invention consists, primarily, in the novel pump hereinafter set 50 forth; and the invention consists, furthermore, in the novel arrangements and combinations of the various devices and parts, as well as in the details of the construction of the same, all of which will be more fully de-

scribed in the following specification, and 55 then finally embodied in the clauses of the claims which are appended to and which form an essential part of this specification.

The invention is clearly illustrated in the accompanying drawings, in which:— 60

Figure 1 is a vertical sectional representation of a pump, embodying the principle of this invention, the adjustable or regulatable parts being set, so that the liquid will be forced from and through the pump in the 65 directions indicated by the arrows in said figure. Fig. 2 is a vertical section of the lower end-portion of the pump-casing or cylinder and its base, with the plunger or piston and the adjusting or regulating means employed in connection therewith being shown in elevation, said view being made on an enlarged scale. Fig. 3 is a detail vertical section of the respective upper and lower portions of the pump, said view being made on 70 the same scale as Fig. 1, and showing the adjustable or regulatable parts set, so that the liquid will be forced from and through the pump in an opposite direction from that indicated by the arrows in said Fig. 1. Fig. 4 75 is a sectional representation of the same portions of the pump, similar to that shown in said Fig. 3, but the adjustable or regulatable parts being set so that, during the reciprocatory movements of the plunger or 80 piston, the liquid will be sucked into the end of the pump-casing or cylinder and then again forced out of the same end of the pump-casing or cylinder. Fig. 5 is a horizontal section, taken on line 5—5 in said Fig. 1 of 85 the drawings; Fig. 6 is a similar section, taken on line 6—6 in Fig. 1; and Fig. 7 is a horizontal section, taken on line 7—7 in said Fig. 1, all of said sections being made on an 90 enlarged scale. 95

Similar characters of reference are employed in all of the above described views, to indicate corresponding parts.

Referring now to the said drawings, the reference-character 1 indicates a complete 100 pump, showing one embodiment of our present invention, the same comprising a suitable pump-casing or cylinder 2, which is preferably provided at its lower and upper ends with the externally screw-threaded portions 105 3 and 4. The lower screw-threaded end-portion 3 of the cylinder is suitably screwed into an internally screw-threaded receiving socket

6 formed in a suitably shaped base, as 5. This base or foot-piece is usually provided with another internally screw-threaded receiving socket 7, into which is screwed the 5 lower and externally screw-threaded portion 9 of a tubular member or cylinder 8, said cylinder being provided at the top with a screw-portion 10 for the closing of the upper end of said cylinder 8 by means of a suitable 10 cap, as 11. The said tubular member or cylinder 8 is provided in its side with an opening 12, and 13 indicates a piece of piping or nozzle, suitably secured upon the outside of the cylinder 8, in any well-known manner, 15 over said opening 12. The said piping or nozzle 13 is for the purpose of attaching thereto a flexible or other suitable connection, so as to establish a communication between said cylinder 8 and one opening or end 20 of the system of piping which is to be cleansed. Communication is established between the pump-casing or cylinder 2 and said tubular member or casing 8 by means of a duct 14 which has been suitably formed in 25 the base or foot-piece 5, as will be clearly understood from an inspection of Fig. 1 of the drawings.

Suitably screwed upon the upper screw-threaded portion 4 of the cylinder 2 is a suitable cap or closing member 15, said member being made with an opening 16, and a stuffing-box 17 provided with a suitable packing 18. The cap or closing member 15 is also provided with an opening, as 19, with which 30 is suitably connected a short piece of piping or nipple, as 20, for the attachment thereto of a flexible or other suitable connection, so as to establish a communication between the upper portion of the cylinder 2 and another 35 opening or end of the same system of piping which is to be cleaned. Movable arranged in said stuffing-box 17, so as to extend through the opening 16 and into the interior of the pump-casing or cylinder 2 is a tubular 40 plunger or piston-operating stem 21, said piston-stem being provided upon its upper end-portion with a screw-thread 22, a suitable handle 23 being arranged and secured upon said end-portion by means of suitable 45 nuts 24 and 25, or other suitable fastening means, as will be clearly evident. Screwed upon that portion of the stem 21 which projects above the nut 24 is a screw-cap 26 having in its upper closed end an opening 27, as 50 shown in Fig. 1 of the drawings, and for the purposes to be presently described.

Slidably disposed within the pump-casing or cylinder 2 is a plunger or piston 28 which is provided in its cylindrical surface with an 55 annular receiving portion 29 in which is arranged any suitable packing 30 in frictional sliding contact with the inner surface-ports of the casing or cylinder 2. Extending upwardly from said plunger or piston 28 are 60 uprights or posts 31 which are connected by

means of a cross-piece 32, all arranged to provide a substantially yoke-shaped suspension means, as will be evident. The said cross-piece 32 is made with an opening 33 and an enlarged and internally screw-threaded receiving socket 34 into which the lower and screw-threaded end-portion 35 of the tubular piston-stem is screwed, a perforated washer 36 and perforated packing-ring or gasket 37 being arranged in said 70 socket 34 beneath the edge of said end of the piston-stem, substantially as illustrated in Figs. 1, 3 and 4 of the drawings. The plunger or piston 28 is made with an opening 38, formed at its upper end with a valve-seat 39 and at its lower end with a valve-seat 40. Loosely and slidably disposed in said opening 38 is a plug 41 formed at its upper end with an annular and cone-shaped rim 42, adapted to be seated upon said valve-seat 39, and formed at its lower end with an annular and cone-shaped rim 43, adapted to be seated upon said valve-seat 40. In order that the said valve-plug 41 can be arranged in its operative relation to the plunger or piston 28, the lower portion of the plug which is provided with the cone-shaped rim 43 is made in the form of a separable plate or disk 44, formed with a slot 45 and a screw-stud 46, so as to be screwed into a screw-threaded 90 socket 47 in said plug 41 for the purpose of assembling said parts in their operatively connected relation.

Within the upper tubular portion of the piston-stem 21 is a tubular member or element 48 having a pin 48' extending diametrically across the same, and the said pin having its projecting end-portions extending into and slidably arranged in slots or openings 49 suitably disposed in the opposite sides of the piston-stem. The said member or element 48 is internally screw-threaded, as at 50, and screwed into the lower portion of said member or element 48 is the upper screw-threaded portion 52 of a rod 51. This rod 51 extends in a downward direction through the interior of the tubular piston-stem 21, through the openings or holes in the washer 36 and the packing-ring or gasket 37, and through the opening 33 in the cross-piece or bar 32. The lower end-portion of said rod 51 which extends below the under surface of said cross-piece or bar 32 is provided with a screw-threaded part 53 and is screwed into the upper end of a tubular member or thimble 54. The lower open end of said member or thimble is also provided with a screw-threaded part, as 55, and connected therewith, in any suitable manner, is a socketed nut or member 56, the latter being provided in its closed end with a suitable hole 57. Loosely arranged in said hole 57, and retained in place by means of a head or enlargement 59 is a screw or pin 58, the lower and preferably screw-threaded end-portion 130

of which is securely screwed into a screw-threaded receiving socket 60 in the upper portion of the valve-plug 41, whereby all of said parts are assembled in their operative relation, as will be clearly evident from an inspection of the several figures of the drawings. The valve-plug 41, as will be seen more particularly from an inspection of Figs. 2 and 7, is made with longitudinally extending rib-like members, as 61, which, with the interior surface-portions of the opening 38 in the plunger or piston form suitable ducts through which the liquid can flow, at certain times, as will be hereinafter more fully set forth.

Screwed into the upper and internally screw-threaded portion of the previously mentioned member or element 48 is another screw-threaded stem or rod 62, said stem being provided with an annular or other suitably formed shoulder or offset 63 arranged directly against the under surface of the closed end of the screw-cap 26. The stem or rod 62 also has a part 64 which extends into and through the opening 27 in the closed end of the screw-cap 26, a pin 65 which is connected with said part 64 and has its opposite and projecting ends bearing lightly upon the surface of said closed end of the screw-cap 26, retaining said parts in their operatively assembled relations, against displacement, but not interfering with the turning of said screw-threaded stem or rod 62, as will be clearly evident. That the said stem or rod may be turned, from right to left and back again from left to right, the stem or rod is provided upon its upper end with a suitable thumb-nut 66, or other finger-piece.

Having described the general arrangement and combinations of the several devices and parts, to provide a pump embodying the principal features of our present invention, we will now briefly set forth the manner of "setting" the valve-plug, and the manner of operating the pump for variously forcing the liquid into, through, and from the pump-casing or cylinder.

When the parts have been set or adjusted in their relative positions indicated in Fig. 1 of the drawings, and when a reciprocatory movement of the piston-stem 21 is produced by taking hold of the ends of the handle 23, and moving the same back and forth, and thereby producing also a reciprocatory movement of the plunger or piston, the cone-shaped rim 43 of the valve-plug 41 will become firmly seated upon the lower valve-seat 40, during the downward movement of the plunger or piston. The result will be, that any liquid contained in the pump-casing or cylinder 2 will be driven in front of the said plunger or piston 28, from said cylinder 2, through the duct 14, and into the cylinder 8 in which is contained the cleansing compo-

sition. The liquid is forced from said cylinder 8 through the outlet 13, and then into and through the system of piping which is to be cleansed and then back again into the cylinder 2 through the pipe or nipple 20, all as indicated by the arrows shown in said Fig. 1. The adjustment of the parts is such that during the upward stroke or movement of the piston-stem and piston, the valve-plug 41 will assume the position indicated in Figs. 1 and 2 of the drawings, and the plunger or piston can be moved upwardly in the cylinder 2 without any effect upon the liquid. The valve-plug is thus moved alternately from its closing relation with the plunger or piston into its opened relation therewith, so that the plunger becomes operative only during its downward stroke, and a continuous flow of the liquid will be produced through the said cylinder 2 in the one direction only indicated by the arrows in said Fig. 1.

When it is necessary and desirable to reverse the direction of the flow of liquid through the system of piping, and consequently through the pump-casing or cylinder all that is necessary is, by means of the finger-piece 66 to turn the screw-stem 62 from left to right. This movement of said screw-stem will produce a downward movement of the tubular member or element 48 directly within the piston-stem 21, and thereby causes a slight downward movement of the rod 51 within the stem 21, so as to bring the parts connected with and suspended from the lower end-portion of rod 21 into the adjusted positions indicated in Fig. 3 of the drawings. The result of this will be that when the plunger or piston 28 moves in an upward direction, then the cone-shaped rim 42 closes down upon the valve-seat 39 of said plunger or piston and during the upward stroke of said plunger or piston the liquid will be forced from the cylinder 2 through the nipple 20 into and through the system of piping which is to be cleansed, to and into the cylinder 8, and then through the duct and passageway 14 into the lower end of the pump-casing or cylinder 2. The adjusted arrangement of the parts, as will be seen from said Fig. 2 of the drawings, is such that during the downward or returning stroke of the piston or plunger, the ducts of the said piston or plunger will remain open so that there can be no action of the piston and plunger upon the liquid within the cylinder 2 during such return movement of the said piston.

The construction of the parts is such that the various adjustments can be quickly made so that, at will of the operator and as necessity may demand, the flow of the cleansing liquid through the system of piping which is being cleansed can be easily and quickly alternated so as to obtain the best results.

In some instances, it may be desired to

use the pump in the manner of the usual suction pump. When this is desired, the parts are brought into their adjusted relations, indicated in Fig. 4 of the drawings, 5 and the plug 41 is immovably held in the position shown, by having moved the rod 51 in a still further downward direction, so as to bring the nut 56 tightly down upon the upper surface of the said plug 41. It will 10 thus be evident, from an inspection of said Fig. 4 of the drawings, that when the piston is moved in an upward direction, and the valve-plug being fixed, a suction is produced for sucking the liquid into the pump-casing; 15 and, that during the return stroke of the piston the liquid will be forced from the said cylinder 2 and from the same end into which it had been previously sucked. By again turning the screw-rod 62 in the direction 20 from right to left, the proper adjustment can be made so as to again bring the valve-plug 61 into anyone of the adjusted positions indicated in said Figs. 3 and 4 of the drawings.

From the foregoing description of our 25 present invention, it will be seen that we have devised a simple and effectively operating pump adapted for the purposes herein above set forth; and one, in which the liquid can be forced in a continuous stream through the 30 pump-casing in either direction, or can be sucked into one end thereof and again forced out of the end according to the purposes to which the pump is to be placed.

We are fully aware, that changes may be 35 made in the general arrangements and combinations of the devices and parts, as well as in the details of the construction of the same, without departing from the scope of our present invention, as defined in the claims 40 which are appended to this specification. Hence, we do not limit our invention to the exact combinations and arrangements of the devices and parts as described in the foregoing specification, and as illustrated in the 45 accompanying drawings, nor do we confine ourselves to the exact details of the construction of any of the said parts.

1. A pump comprising a cylinder, a plunger having an opening provided with an upper and lower valve-seat, and a valve-plug movably arranged in said opening, and means for seating said valve-plug upon either valve-seat, and mechanism for rigidly setting said valve-plug in its closing relation 50 with the opening in said plunger, substantially as and for the purposes set forth.

2. A pump comprising a cylinder, a plunger having an opening provided with an upper and lower valve-seat, a valve-plug movably arranged in said opening, a tubular stem connected with said plunger and extending from said cylinder, said stem being provided with means for producing reciprocatory movements of the stem and plunger, and ad-

justing devices arranged within and extending from said stem, for seating the valve-plug upon either valve-seat, and means connected with said adjusting devices for rigidly seating said valve-plug in its closing relation with the opening in said plunger, substantially as and for the purposes set forth. 65 70

3. A pump comprising a cylinder, a plunger having an opening provided with an upper and lower valve-seat, a valve-plug movably arranged in said opening, a tubular stem 75 connected with said plunger, means on said stem for producing reciprocatory movements of the stem and plunger, a tubular and internally screw-threaded member slidably arranged in the upper portion of said stem, a screw-threaded rod for causing the movement of said sliding member, and a rod connected with said member and extending through said tubular stem, and a means of connection between said rod and the valve-plug for seating the latter upon either valve-seat, and means for rigidly setting said valve-plug in the closing relation with the opening in said plunger, substantially as and for the purposes set forth. 80 85

4. A pump comprising a cylinder, a plunger having an opening provided with an upper and a lower valve-seat, a valve-plug movably arranged in said opening, uprights upon 90 said plunger, and a cross-piece joining the said uprights, said cross-piece being provided with an opening, a tubular stem connected with said cross-piece, means on said stem for producing reciprocatory movements of the stem and plunger, a rod movably arranged 95 within said stem, said rod extending at its lower end-portion from said cross-piece, and a means of connection between the lower end-portion of the rod and the valve-plug for seating the valve-plug upon either valve-seat, and means for rigidly setting said valve-plug in its closing relation with the opening in 100 said plunger, substantially as and for the purposes set forth. 105

5. A pump comprising a cylinder, a plunger having an opening provided with an upper and a lower valve-seat, a valve-plug movably arranged in said opening, uprights upon 110 said plunger, and a cross-piece joining the said uprights, said cross-piece being provided with an opening, a tubular stem connected with said cross-piece, means on said stem for producing reciprocatory movements of the stem and plunger, a tubular and internally screw-threaded member slidably 115 arranged in the upper portion of said stem, a screw-threaded rod for causing the movement of said sliding member, a second rod connected with said member and extending through said tubular stem, said rod extending at its lower end-portion from said cross-piece, and a means of connection between the lower end-portion of the rod and the 120 125

valve-plug for seating the valve-plug upon either valve-seat, and means for rigidly setting said valve-plug in its closing relation with the opening in said plunger, substantially as and for the purposes set forth.

6. A pump comprising a cylinder, a plunger having an opening provided with an upper and a lower valve-seat, a valve-plug movably arranged in said opening, uprights upon said plunger, and a cross-piece joining the said uprights, said cross-piece being provided with an opening, a tubular stem connected with said cross-piece, means on said stem for producing reciprocatory movements of the stem and plunger, a rod movably arranged within said stem, said rod extending at its lower end-portion from said cross-piece, a thimble upon said end-portion of the rod, a socketed nut connected with 15 said thimble, and a means of connection between said nut and the valve-plug, said means being movably arranged for seating the valve-plug upon either valve-seat, and means for rigidly setting said valve-plug in 20 its closing relation with the opening in said plunger, substantially as and for the purposes set forth.

7. A pump comprising a cylinder, a plunger having an opening provided with an upper and a lower valve-seat, a valve-plug movably arranged in said opening, uprights upon said plunger, and a cross-piece joining the said uprights, said cross-piece being provided with an opening, a tubular stem connected with said cross-piece, means on said stem for producing reciprocatory movements of the stem and plunger, a rod movably arranged within said stem, said rod extending at its lower end-portion from said cross-piece, 35 a thimble upon said end-portion of the rod, a socketed nut connected with said thimble, said nut being provided with a hole, a screw extending from said valve-plug through the hole in said nut, and a head on said screw, 40 said head being movably arranged in said socketed nut for seating the valve-plug upon either valve-seat, and means for rigidly setting said valve-plug in its closing relation with the opening in said plunger, substantially as and for the purposes set forth.

8. A pump comprising a cylinder, a plunger having an opening provided with an upper and a lower valve-seat, a valve-plug movably arranged in said opening, uprights 55 upon said plunger, and a cross-piece joining the said uprights, said cross-piece being provided with an opening, a tubular stem connected with said cross-piece, means on said stem for producing reciprocatory movements 60 of the stem and plunger, a tubular and internally screw-threaded member slidably arranged in the upper portion of said stem, a screw-threaded rod for causing the movement of said sliding member, a second rod

connected with said member and extending 65 at its lower end-portion from said cross-piece, a thimble upon said end-portion of the rod, a socketed nut connected with said thimble, and a means of connection between said nut and the valve-plug, said means being movably arranged for seating the valve-plug upon either valve-seat, and means for rigidly setting said valve-plug in its closing relation with the opening in said plunger, substantially as and for the purposes set forth.

9. A pump comprising a cylinder, a plunger having an opening provided with an upper and a lower valve-seat, a valve-plug movably arranged in said opening, uprights 70 upon said plunger, and a cross-piece joining the said uprights, said cross-piece being provided with an opening, a tubular stem connected with said cross-piece, means on said stem for producing reciprocatory movements 75 of the stem and plunger, a tubular and internally screw-threaded member slidably arranged in the upper portion of said stem, a screw-threaded rod for causing the movement of said sliding member, a second rod 80 connected with said member and extending at its lower end-portion from said cross-piece, a thimble upon said end-portion of the rod, a socketed nut connected with said thimble, said nut being provided with a hole, a screw 85 extending from said valve-plug through the hole in said nut, and a head on said screw, said head being movably arranged in said socketed nut for seating the valve-plug upon either valve-seat, and means for rigidly setting said valve-plug in its closing relation with the opening in said plunger, substantially as and for the purposes being set forth.

10. In a pump, the combination, with a foot-piece, of a pump casing and a cylinder 90 both connected with said foot-piece, a means of communication between the pump-casing and said cylinder, a plunger in said casing, said plunger having an opening provided with an upper and a lower valve-seat, a valve-plug 95 movably arranged in said opening, uprights upon said plunger, and a cross-piece joining the said uprights, said cross-piece being provided with an opening, a tubular stem connected with said cross-piece, means on said stem for producing reciprocatory movements 100 of the stem and plunger, a tubular and internally screw-threaded member slidably arranged in the upper portion of said stem, a screw-threaded rod for causing the movement 105 of said sliding member, a second rod connected with said member and extending at its lower end-portion from said cross-piece, a thimble upon said end-portion of the rod, a socketed nut connected with said thimble, 110 said nut being provided with a hole, a screw extending from said valve-plug through the hole in said nut, and a head on said screw, 115 said head being movably arranged in said socketed nut for seating the valve-plug upon either valve-seat, and means for rigidly setting said valve-plug in its closing relation with the opening in said plunger, substantially as and for the purposes being set forth.

said head being movably arranged in said socketed nut for seating the valve-plug upon either valve-seat, and means for rigidly setting said valve-plug in its closing relation with the opening in said plunger, substantially as and for the purposes set forth.

In testimony that we claim the invention

set forth above we have hereunto set our hands this 21st day of December, 1907.
